AUTOMOBILE LATCH

Arthur A. Kraft, St. Louis, Mo., assignor to William H. Biggs, St. Louis, Mo., as trustee

Application October 23, 1937, Serial No. 170,542

5 Claims. (Cl. 292—332)

This invention relates to closure fasteners of a type particularly adapted for automobile doors.

An object of this invention is to provide on a door a latch which will make the door easy to close. Specifically it is to provide a latch with a bolt having means for holding the bolt in retracted position, which means are displaceable by a keeper to release the bolt upon closing the door.

Another object of the invention is to provide a door latch having a bolt retractable by outside retracting mechanism and inside retractable mechanism with means operable by the inside retractable mechanism for rendering the outside retractable mechanism inoperative.

Another object of the invention is to provide a door latch retractable by a spindle having means carried by the spindle for disassociating the spindle from the bolt to prevent unauthorized manipulation.

Another object of the invention is to provide latch mechanism with a retractable bolt, a control lever and retracting mechanism and having a single spring operable to urge each of the three elements toward a normal position, and operable to cause the movement of any of the three elements without necessarily operating the other two elements.

In addition there is the general object to provide a door latch which is efficient in operation, economical to manufacture, and which may be readily disassembled for repair.

Other and specific objects will be apparent from the following detail description, taken in connection with the accompanying drawings.

Fig. 1 is an elevation showing a latch embodying this invention.

Fig. 2 is an elevation partly in section showing the parts after they have been moved by outside retracting mechanism to retract the bolt.

Fig. 3 is an elevation partly in section showing the position of the parts after the control lever has been moved to non-operative position.

Fig. 4 is a cross section approximately on line 4—4, Fig. 1.

Fig. 5 is a cross section on line 5—5, Fig. 2.

Fig. 6 is a detail partly in section showing a spindle which constitutes a part of the outside retracting mechanism and showing means mounted on the spindle for rocking the control lever.

The latch mechanism is mounted in or on the casing or frame which includes a front plate 1, a selvage plate 2 and a cover or retaining plate 3. The front plate and selvage plate are prefer-

ably integral and formed from sheet metal by dies. The retaining plate 3, also preferably formed from sheet metal, has downwardly extending flanges 4 for spacing it from the front plate 1 and is secured to the front plate by a screw 5 which passes through the retaining plate 3 and is threaded in the front plate 1.

A retractable bolt 6 is mounted for sliding movement and has a head 7 passing through an orifice in the selvage plate 2 and a shank 8, preferably of sheet metal, secured as a specifically shown in the drawings by a rivet 9 to the head 7. The shank of the bolt has a longitudinal slot 10 and the bolt is guided in part by a pin 11 secured to the front plate 1 and having a head 12. For assembling the bolt in the casing 15 or frame, an enlargement 13 is provided at the forward end of the slot 10 to pass the head 12 of the pin.

A guide and bushing member 14 is secured to the front plate and has its front edge surrounding a portion of the orifice in the selvage plate, as shown in Figs. 4 and 5. A second bushing member 15 has a flat portion secured to the inner face of the selvage plate and an outturned portion 16 extending about the edge of the orifice 25 over that portion not covered or protected by the bushing member 14. The bushing member 14 has a longitudinal part which serves as a guide for the bolt 6.

A retaining pin 17 is mounted for rotation on the front plate 1 and has a head 18 of the peculiar conformation as shown with a cleft 19 for engagement by a screw driver. A stop 20 for the head 18 of the retaining pin is formed on the front plate 1. The head 18 has a straight edge 21 for engagement with the stop 20 and a straight edge 22 for engagement with the top edge of the bolt, that is the top edge of the shank 8. The head 18 also has its outer edge 23 positioned to engage a stop or lug 24 on the upper surface of the shank 8 of the bolt.

It will now be understood that the retaining member 17 holds the bolt in assembly on the casing, but by turning the pin 17 in a clockwise direction the bolt 6 may be retracted to bring the head 12 of the pin 11 into registry with the slot enlargement 13, thereby permitting the removal of the bolt and also providing for assembly of the bolt on the casing.

The outer end or edge of the bolt is bevelled, 50 as shown in Figs. 4 and 5, the bevel 25 extending outwardly from the inner to the outer longitudinal face of the bolt. The outer face of the bolt has a longitudinal groove 26 terminating near the end of the bolt in a deeper recess 27; the inner 55

edge of the recess cooperating with a ball 28 to automatically hold the bolt in retracted position until the ball is displaced. The ball 28 is urged outwardly by a spring 29. The ball 28 and spring 29 are retained in a housing 30, the housing being secured to the casing by rivets 31 passing through flanges 32, bushing member 15 and selvage plate 2, thereby also holding the bushing member and housing in assembly.

5 The spring 29 urges the ball 28 outwardly so that it bears in the groove 26 of the bolt 6 and against the edge 16 of the bushing surrounding the orifice in the selvage plate. The parts are so proportioned that when the bolt is in extended 10 position, as shown in Fig. 4, the outer edge of the ball will be substantially even with the outer edge of the selvage plate 2. But when the bolt is retracted the larger recess 27 permits the ball to be extended, as shown in Fig. 5, so that its 15 outer edge extends substantially beyond the selvage plate, while by wedging between the edge 16 about the orifice and the inner surface of the recess the bolt is retained in its retracted position until the ball 28 is displaced. The ball is 20 displaced normally by striking against a keeper when the door upon which the latch is mounted is closed. The advantages of these functions 25 may be apparent. Ordinarily when a door carrying a latch is open, the bolt is permitted to resume its extended position and the force in closing the door is expected to retract the bolt by 30 action between the keeper and a bevel on the front end of the bolt. Thus retracting the bolt in closing a door requires considerable force.

35 But with the present invention, when the door is closed only sufficient force is needed to cause necessary action of the latch as will be required to displace the ball 28, since the bolt will be held in retracted position until the door is in 40 position to permit the bolt to slide into its keeper. Nevertheless the arrangement of the present device is such that a bevel is provided to enable the door to be closed in a usual manner in case the ball for any reason should be ineffective to 45 retain the bolt, or in case the ball should be accidentally displaced while the door is open.

The bolt 6 is constructed and arranged to be 50 retracted by either inside retracting mechanism or outside retracting mechanism, and means are provided operable either by the inside retracting mechanism or by mechanism mounted on the outside mechanism for locking the latch. This locking is done by means of a control lever 33 through which the outside retracting mechanism 55 may have engagement with the bolt, but which when moved will prevent engagement between the outside retracting mechanism and the bolt.

The control lever is pivotally mounted on the shank 8 of the bolt 6 by a pin 34 and is a lever 60 of the first class having a downwardly extending arm 35 and a rearwardly extending arm 36. The control lever is urged in a clockwise direction by a spring 37, later to be described in some detail, which has an end bearing against a lug 65 38 extending laterally from the arm 35 of the control lever while its movement in a clockwise direction is limited by engagement between a forwardly extending lug 39 positioned to strike the rear edge of the head 7 of the bolt.

70 The rearwardly extending arm 36 on the control lever has a lug or abutment 40, which when the lever is in operating position may be engaged by a dog 41 on a slide 42 movable by the outside retracting mechanism. If the control lever 33 is rocked in a counter-clockwise direc-

tion the abutment 40 may be raised sufficiently to move it out of the path of the dog 41 on the slide and in this position, referred to herein as non-operative position, the outside retracting mechanism will have no connection with the bolt 5 and cannot move it although such mechanism is allowed freedom of movement.

The inside retracting mechanism includes a link 43 having a pin 44 passing through the slot 10, the pin having a crosshead 45. It will be 10 understood that the link is operable by a lever extending inside of the closure to which the latch is applied; that is, for instance, by a lever on the inside of the door of an automobile and furnishes means for unlatching the fastener from 15 the inside. When the bolt is moved by the outside retracting mechanism, the pin 44 slides in the slot 10, thus permitting the latch to be operated from the outside independently of the inside retracting mechanism. It will also be apparent that when the bolt is retracted by movement of the link 44 to the right, as shown in the drawing, the abutment 40 merely moves away from the dog 41 on the slide 42, so that the latch may be operated from the inside independently 20 and without manipulating or moving the outside retracting mechanism.

A cooperating relationship is provided between the link 43 and the control lever 33 so that by overthrowing the link 43 the lever may be raised. 30 This cooperative relationship includes a cam surface 46 at the end of the rear arm 36, which is in the path of the outer end of the link pin 44. It will be understood that the extension of the link pin 44, for this purpose, is in reality a part 35 of the link 43. It will be apparent, therefore, that by moving the link 43 to the left the extension on the link pin 44 will engage the cam surface 46 on the control lever, rocking the control lever 33, thereby raising its abutment 40 out of 40 the path of the dog 41 so that when the link has been so moved connection is broken between the bolt and the outside retracting mechanism.

The outside retracting mechanism includes a spindle 47 which carries means for also rocking 45 the control lever to non-operative position. This means includes a sliding pawl 48 passing diametrically through the spindle 47 and positioned to engage the downwardly extending arm 35 of the control lever when moved outwardly, to the right 50 as shown in Fig. 1, or upwardly as shown in Fig. 6. The pawl can be projected by a key 49 through a lock shaft 50 which has at its end an eccentric pin 51. It will be understood that the construction and arrangement of the pawl operable by 55 a lock shaft and by a key is old and well known in other combinations, and need not be described in detail. And it will now be understood that upon turning the key 49 the pawl 48 may be extended to rock the control lever placing it in 60 non-operative position and placing the bolt out of control of the outside retracting mechanism.

The slide 42 is supported for longitudinal movement by a lug or flange 52 secured to or struck out from the front plate 1. The slide is operated 65 by a cam or dog 53 journaled in the front plate 1 and retaining plate 3 and positioned therebetween. It has centrally a square opening to receive the inner end 54, which is square in cross section, of the spindle 47. The spindle 47 extends outwardly from the closure upon which the fastener is placed and has a handle 55 for manual operation. It may now be understood that when the control lever 33 is in operative position the spindle 47 may be turned by the handle 55 70 75

thereby rotating the cam or dog 53, which engages the front end of the slide 42; and because of the engagement of the dog 41 on the slide 42 with the abutment 40 on the control lever the bolt 6 will be retracted.

5 A novel spring arrangement is provided whereby the parts are urged to an initial or normal position by the single spring 37. The spring 37, which is spiral in form, has its outer end bearing against the lug 38 on the control lever 33, as previously described, and has its inner end secured to a spindle or pin 56 journalled in the plates 1 and 3. The pin 56 is secured to a cam 57 which bears against an arm 58 integral with a segmented gear 59, which is also journalled for rotation between the plates 1 and 3 and which is in mesh with a rack on the lower edge of the slide 42. It will now be seen that the spring 37 through its connection at its inner end urges the outside 10 retracting mechanism (including the slide 42, cam 53 and spindle 47) to a normal position while the outer end urges the control lever toward operative position and urges the bolt to extended position. Any of these functions may be 15 performed by the spring with respect to a particular part without regard to the condition of either of the other parts. That is to say, the control arm will be urged toward normal position whether the bolt is extended or retracted, and regardless of the position of the outside retracting mechanism; the bolt will be urged toward extended position regardless of the position of the control lever or the bolt.

20 The simplicity of the device and its economy of construction will be apparent from the foregoing description. Most of the parts may be manufactured economically by stamping from sheet metal. The assembly and disassembly of the device is simple. Except for turning the retaining pin 47, removal and replacement of the spring 37 and the screw 5, the device may be speedily disassembled and reassembled without the use of 25 tools.

30 Various changes may be made in the details of construction, within the scope of the appended claims, without departing from the spirit of this invention, and parts of the invention may be used without the whole.

35 I claim:

1. In a latch, the combination comprising a 40 selavage plate, a sliding bolt passing through an orifice in the selavage plate and having a recess

5 in a longitudinal face adjacent its end, a spring urging the bolt toward extended position, and a ball adapted to rest in said recess when the bolt is retracted and by wedging between the edge of the recess and the edge of the orifice to hold the bolt in retracted position until the ball is displaced.

10 2. In a latch, the combination comprising a selavage plate, a sliding bolt passing through an orifice in the plate having a bevelled outer edge extending inwardly from a longitudinal face and a recess in said longitudinal face adjacent its outer end, a spring urging the bolt toward extended position, and a ball adapted to rest in said recess when the bolt is retracted and by wedging between the bolt and the edge of the orifice to hold the bolt in retracted position until the ball is displaced.

15 3. In a latch, the combination comprising a selavage plate, a sliding bolt passing through an orifice in the selavage plate and having a recess in a longitudinal face adjacent its end, a spring urging the bolt toward extended position, a housing inwardly from said selavage plate and along the bolt, a ball in the housing, and a spring in the housing beyond the ball arranged and adapted to cause the ball to rest in said recess when the bolt is retracted and by wedging between the bolt and the edge of the orifice to hold the bolt in retracted position until the ball is displaced.

20 4. In a latch, the combination comprising a selavage plate, a sliding bolt passing through an orifice in the selavage plate and having a groove in the longitudinal face enlarged near the end of the bolt, a spring urging the bolt toward extended position, and a ball supported and adapted to engage in the groove and to rest in the enlarged portion thereof when the bolt is retracted and by wedging between the edge of said enlarged portion and the edge of the orifice to hold the bolt in retracted position until the ball is displaced.

25 5. In a latch the combination comprising a selavage plate, a sliding bolt passing through an orifice in the selavage plate and having a recess in a longitudinal face adjacent its end, a spring urging the bolt toward extended position, and a ball positioned to lie in engagement with and along said longitudinal face when the bolt is in retracted, extended and intermediate positions, and to rest in said recess when the bolt is retracted and by wedging between the edge of the recess and the edge of the orifice to hold the bolt in retracted position until the bolt is displaced.

30 ARTHUR A. KRAFT.
